UNITED STATES PATENT OFFICE.

FRANK TAYLOR CABLE, OF QUINCY, MASSACHUSETTS, ASSIGNOR TO ELECTRIC BOAT COMPANY, OF BAYONNE, NEW JERSEY, A CORPORATION OF NEW JERSEY.

FUEL-FEED FOR HYDROCARBON-ENGINES.

No. 849,048.

Specification of Letters Patent.

Patented April 2, 1907.

Application filed October 8, 1906. Serial No. 337,945.

To all whom it may concern:

Be it known that I, FRANK TAYLOR CABLE, a citizen of the United States, residing at Quincy, county of Norfolk, State of Massachusetts, have invented certain new and useful Improvements in Fuel-Feeds for Hydrocarbon-Engines; and I do hereby declare the following to be a full, clear, and exact description of the invention, such as will enable others skilled in the art to which it appertains to make and use the same.

The object of the invention is to provide a simple and efficient fuel-feed mechanism for hydrocarbon-engines whereby a constant supply of liquid may be maintained in the carbureter irrespective of the speed of the engine.

In the accompanying drawings, Figure 1 is an elevation of a hydrocarbon-engine installation involving the invention. Fig. 2 is a vertical section through the float-chamber and valve-casing.

In explosive-engine installations of large power or multiple units, or where an installation will not admit of the gravity-feed arrangement because of the location of the supply-tank at a lower level than that of the carbureter, it is advantageous or necessary to supply the liquid fuel to the carbureter by means of a pump or other positive feeding means. The difficulty which exists in regulating such a positive feed in exact accordance with the different speeds of the engine has given rise to the provision of means to take care of the overflow and prevent the carbureters being flooded.

The present invention contemplates, in connection with such a positive or power feed for the liquid fuel, means to insure a constant level of fuel in the carbureter at all speeds, the nature of which will be understood from a consideration of the accompanying drawings and the following description, which illustrate and describe the preferred form.

In the accompanying drawings, E indicates an explosive-engine of any approved type, which receives an explosive mixture from the carbureter a. Said carbureter may be of any of the well-known types adapted to maintain a constant level of gasoline or the like, but is preferably given the

form shown in the drawings, which includes a central mixing-chamber b, surrounded by a liquid-chamber c, said chambers being connected by an upwardly-inclined duct e, controlled by a needle-valve f. The explosive mixture of air and hydrocarbon vapor is delivered from the mixing-chamber to the engine by a suitable inlet-pipe d, as will be understood.

The gasoline or other liquid fuel is supplied to the carbureter from a tank or reservoir h, which may be located at any convenient point, a supply-pipe g serving to convey the liquid from the tank to the carbureter. Connected to the supply-pipe g is some positive means for maintaining a constant supply of gasoline or the like, and said positive means may conveniently consist of the pump, as p, driven from the shaft of the engine.

An overflow-pipe w is connected to the carbureter in proper relation to maintain the desired depth of gasoline or the like in the chamber c of the carbureter, and said overflow-pipe w is connected to a float-chamber i, into which the liquid overflow from the carbureter is delivered. Said float-chamber i is adapted to be connected in the supply-pipe g between the pump p and the overflow-pipe w and for this purpose is provided with a nipple i' on its bottom, which constitutes a casing for a valve r, adapted to close against a lower seat u or an upper seat t, as will be hereinafter more particularly explained.

Within the chamber i there is mounted a float j, of cork or other suitable material, which is swung from the top of the chamber i by means of suitable links l, which constitute levers of the first class, one end being pivoted to the float and the other end engaging a collar n on the rod k of the valve r, said rod passing centrally through the float. The collar n is conveniently secured to the rod k by means of a sleeve m and a nut o. It will be noted that as the float j rises in the chamber i the valve r will be moved downwardly, and, vice versa, as the float falls the said valve will be moved upwardly.

The operation of the apparatus hereinbefore described is as follows: Under all conditions of operation the level of the liquid in the chamber c of the carbureter is to be main-

tained constant. The pump p in the supply-pipe g takes the gasoline or other fluid constituent from the tank or reservoir h and forces it into the chamber c of the carbureter. 5 The amount of fluid delivered to the carbureter by the pump will of course depend upon the speed of the pump, which is governed by that of an engine. As long as the gasoline supplied to the carbureter is taken up in the 10 explosive mixture about as fast as it is delivered by the pump there will be little or no overflow from the carbureter by way of the pipe w , and consequently the float in chamber i will occupy its lower position, as shown 15 in Fig. 2, thereby closing the valve r against valve-seat t and disengaging said valve from the seat u , thereby fully opening communication between the pump and the supply-tank h . Should the speed of the pump increase, or for 20 any other reason should the amount of gasoline supplied to the carbureter exceed that required for working the engine, the excess will overflow by way of pipe w and enter the float-chamber i . As the overflow increases 25 the float j will rise, thereby seating valve r against the lower valve-seat u , closing communication between the pump and the supply-tank and opening up direct communication between the pump and the float-chamber, 30 so that the fluid contained in the latter will be pumped by way of the supply-pipe g back into the carbureter and will circulate in the closed system comprising the supply-pipe g , chamber c of the carbureter, overflow-pipe w , float-chamber i , until the quantity of 35 the overflow has been so far reduced as to fail to raise the float j , which will accordingly fall and again elevate the valve r to close the exit of the float-chamber and open a through- 40 passage from supply-tank h to the pump p . This operation is entirely automatic and insures a constant level of gasoline in the carbureter without the least danger of flooding the same irrespective of the speed of the engine and the feed-pump. 45

The float-chamber i is conveniently provided with a vent v for carrying off any vapors which may collect in the chamber, and in order to observe the height and condition 50 of the liquid in the float-chamber the latter may be provided with a suitable sight-glass.

Having thus described my invention, what I claim is—

1. In a fuel-feeding system for hydrocar-

bon-engines, the combination of carbureter, 55 a supply-pipe leading thereto, an overflow-pipe leading therefrom, a supply-tank, a float-chamber connected with the overflow-pipe and with the supply-pipe, a valve operated by the float to control the communication of the supply-pipe with the tank and the float-chamber respectively, and means in the supply-pipe between the float-chamber and the carbureter. 60

2. In a fuel-feeding system for hydrocarbon-engines, the combination of a constant-level carbureter, a supply-pipe leading thereto, an overflow leading therefrom, a supply-tank, a chamber connected with the overflow-pipe and with the supply-pipe, a float in 70 said chamber, a valve operated by said float to control the communication of the supply-pipe with the tank and the float-chamber respectively, and a pump in the supply-pipe 75 between the float-chamber and the carbureter.

3. In a fuel-feeding system for hydrocarbon-engines, the combination of a constant-level carbureter, a supply-pipe and an overflow-pipe connected thereto, a supply-tank, 80 a pump in the supply-pipe, and means regulated by the overflow from the carbureter for connecting the pump-inlet to the supply-tank or to the overflow-pipe. 85

4. In a fuel-feeding system for hydrocarbon-engines, a carbureter having a liquid-chamber and a mixing-chamber and a regulable valve between the said chambers, and means for maintaining a given level in the liquid-chamber, comprising a supply-tank, a pipe connecting said tank with the liquid-chamber of the carbureter, an overflow-pipe 90 connected to said liquid-chamber, a float-chamber connected to said overflow-pipe and to said supply-pipe, a float in said float-chamber, a valve operated by said float to control the communication of the supply-pipe with the tank and the float-chamber respectively, and a pump in the supply-pipe 95 between the float-chamber and the carbureter. 100

In testimony whereof I affix my signature in presence of two witnesses.
